CLAIM

I claim the ornamental design for a wine glass container device with lid, as shown and described.

DESCRIPTION

FIG. 1 is an in use top perspective view of a wine glass container device with lid showing my new design;

FIG. 2 is a side elevational view thereof;

FIG. 3 is a top plan view thereof; and,

FIG. 4 is a bottom plan view thereof.

The broken lines in FIGS. 1, 2 and 4 are for environmental purposes only and form no part of the claimed design.
